COMBINED PEN AND HOLDER THEREFOR

Joseph A. Barnett, Chicago, Ill., assignor to
A. B. A. Corporation, Chicago, Ill., a corporation of Illinois

Application September 3, 1949, Serial No. 4,851

Term of patent 14 years

(Cl. D74—1)

To all whom it may concern:

Be it known that I, Joseph A. Barnett, a citizen of the United States, residing at Chicago, in the county of Cook and State of Illinois, have invented a new, original, and ornamental Design for Combined Pen and Holder Therefor, of which the following is a specification, reference being had to the accompanying drawing, forming a part thereof.

Fig. 1 is a perspective view of a combined pen and holder therefor, showing my new design, the broken lines being for illustrative purposes only;

Fig. 2 is a perspective view showing the pen separated from the holder.

I claim:

The ornamental design for a combined pen and holder therefor, substantially as shown.

JOSEPH A. BARNETT.
